UNITED STATES PATENT OFFICE

105,149

DESIGN FOR A HAT DISPLAY RACK

Edwin M. Stroock, New Rochelle, N. Y.

Application April 15, 1937, Serial No. 68,798

Term of patent 3½ years

To all whom it may concern:

Be it known that I, Edwin M. Stroock, a citizen of the United States of America, residing at New Rochelle, Westchester county, State of New York, have invented a new, original, and ornamental Design for a Hat Display Rack, of which the following is a specification, reference being had to the accompanying drawing, forming a part thereof, wherein the figure is a perspective view of a hat display rack showing my new design. The cross-sectional contour of the element standing on the base is circular throughout.

I claim:

The ornamental design for a hat display rack substantially as shown and described.

EDWIN M. STROOCK.
